BLADE SHARPENING DEVICE

Guillaume Barsch, Paris, France, assignor to Industrie A. G. Allegro, Emmenbrucke, Switzerland

Application February 8, 1936, Serial No. 63,017
In Germany February 11, 1935

3 Claims. (Cl. 51—214)

The present invention relates to a blade sharpening device and, more particularly, to a device for sharpening the blades of scissors.

The principal object of the invention is to provide a blade sharpening device for use with scissors which will permit scissors to be efficiently sharpened without taking the blades apart and which is readily adaptable for use with scissors of different sizes. As will be apparent from the following specification, the use of the device is not confined to scissors, since it may be used for sharpening blades of various other types.

Other objects and advantages of the invention will be apparent from the following drawings and specification wherein,

Figure 1 is a side elevation of the device with a portion of the base broken away;

Figure 2 is a plan view of the device with portions removed;

Figure 3 is a side elevation of a grinding element holder used in the device;

Figure 4 is a detail perspective view of a portion of the supporting means;

Figure 5 is a detail view of a part of the device;

Figure 6 is a fragmentary view showing a modified form of supporting device;

Figure 7 is a side elevation of a modified form of grinding element; and

Figure 8 is a side elevation, with portions broken away, of a modified form of the device.

Referring to Figures 1 to 5, the base of the device, preferably formed of wood, is designated by the numeral 1 and has a central cutout portion extending through one end of the base, the cutout portion being indicated by the numeral 14. Upon the upper surface of the base 1, there is fixed a grinding element holder 2 in which is secured a stationary grinding element 3. The holder 2 and element 3 are positioned adjacent the inner end of the cutout portion 14 and are bifurcated as shown in Figure 2 so that portions of the grinding element 3 will extend about the sides of the upper portion of the cutout portion 14.

A bracket 8 is secured to the upper side of the base 1, which bracket pivotally supports a second grinding element holder 7 in which is secured a grinding element 5 having a concave grinding face 6. The upper end of the holder 7 is supported in the upper end of the bracket 8 by means of a U-shaped resilient member 11 having inwardly projecting arms 10 arranged to be positioned in any one of a series of vertically spaced apertures 9 in the bracket 8, the arms 10 then projecting into the eye 12 formed at the upper end of the holder 7. The lower end of the

holder 7 has secured thereto one end of a coil spring 13 arranged in the cutout portion 14, the other end of the spring being secured to the base 1.

It will be observed that by the above arrangement, the grinding element 5 may swing outwardly with respect to the grinding element 3 but will be tended to the position shown in Figure 1. The provision of the vertically spaced apertures 9 in the bracket 8 will permit the grinding element 5 to be raised or lowered relative to the grinding element 3 to operate upon blades of different angles of cutting edges. Both the grinding elements 3 and 5 may be removable from their respective holders.

In the use of the device, described above, a pair of scissors may be opened as illustrated in Figure 2 and one blade positioned with its flat surface bearing upon the grinding element 3. The scissors may then be moved in an orbital path as designated by the line 16 in Figure 2, or in a zig-zag path as indicated by the line 17. In either event, the grinding element 5 will be swung relative to the grinding element 3 to act upon the cutting edge of the blade, but the concavity of the grinding face of the element 5 will result in the same angular relation between the two grinding elements, regardless of the swinging movement of element 5.

Figure 6 shows a modified form of securing element used to support a grinding element 6a in the bracket 8, this securing element being designated by the numeral 11a and including a single arm 10a extending entirely through the upper end of the bracket 8. This form of holding means is particularly adapted for use with a grinding element holder 7' having a narrow eyelet 12a at its upper end and, by this arrangement, the holder and the grinding element carried thereby may have a certain degree of lateral movement.

The grinding element 5 described above is of such length that only one end thereof will be exposed to wear and when this end becomes worn, the element may be reversed in its holder.

Figure 7 shows a grinding element 5a which is of but half the length of the element 5 and which will of course be entirely satisfactory, although it is not reversible.

Figure 8 shows a modified form of the device which is of identical construction with the form disclosed in the figures heretofore discussed except that the movable grinding element holder 7a corresponding to the previously discussed holder 7 is supported in a bracket 8a secured

to one end of the base 1 and the spring 13 is connected to the holder 7a intermediate its ends. The grinding element 5b carried by the holder 1a has a convex grinding surface 6', this form of grinding surface being necessary because of the point at which the holder 1a is supported. The holder 7a is adjustable in the bracket 8a by means of the spring element 11 arranged to be fitted in vertically spaced apertures 9 in the same manner as has been described above in connection with Figures 1 to 5. The operation of the Figure 8 device is identical with that of the device disclosed in Figures 1 to 5.

In both forms of my invention the movement 15 of the blade on the stones in an orbital or zigzag path as already referred to, produces along the edge of the blade a diagonal grinding motion which has the most effective sharpening action with the advantage that the sharpening takes 20 place along constantly changing generating lines of the sharpening surfaces. Also, when the device is used for sharpening scissors, it is not necessary to disconnect the blades.

It will also be noted that the invention is of 25 such design that no considerable degree of skill is necessary to obtain a properly sharpened blade.

I claim:

1. A blade sharpening device comprising an 30 element having a flat grinding surface, an ele-

ment having a curved grinding surface, said curved surface element being pivotally mounted for bodily swinging movement longitudinally of the grinding surface of said other element, and means to tend said curve-surfaced element to 5 a predetermined position with respect to said flat-surfaced element.

2. A blade sharpening device comprising an element having a flat grinding surface, an element having a curved grinding surface, said 10 curved surface element being pivotally mounted for bodily swinging movement longitudinally of the grinding surface of said other element, the grinding surface of said second element being 15 of such curvature that at any point in its range of movement relative to said fixed element, its surface adjacent the flat surface of the other element will have the same curvical relation to the grinding surface of said other element.

3. A blade sharpening device comprising a 20 fixed grinding element, a movable grinding element, said fixed grinding element being recessed at one end thereof, said movable grinding element being pivotally mounted for bodily swinging movement longitudinally of said other element and in said recess, and means to tend said 25 movably grinding element to the inner portion of the recess in said fixed element.

GUILLAUME BARSCH. 30
